(57) **CLAIM**

The ornamental design for an interlocking container insert piece as shown and described.

DESCRIPTION

FIG. 1 is top perspective view of an interlocking container insert piece, showing my new design.

FIG. 2 is a bottom perspective view thereof.

FIG. 3 is a left side elevational view thereof.

FIG. 4 is a right side elevational view thereof.

FIG. 5 is a front elevational view thereof.

FIG. 6 is a rear elevational view thereof.

FIG. 7 is a top plan view thereof; and,

FIG. 8 is a bottom plan view thereof.

The interlocking container insert piece is shown with a symbolic break in its length. The appearance of any portion of the article between the break lines forms no part of the claimed design.
